UNITED STATES PATENT OFFICE.

JOHN SCHADE, OF HOLYOKE, MASSACHUSETTS, ASSIGNOR TO NATIONAL BLANK BOOK COMPANY, OF HOLYOKE, MASSACHUSETTS, A VOLUNTARY TRUST ASSOCIATION OF COPARTNERSHIP, HAVING AS TRUSTEES F. B. TOWNE, E. S. TOWNE, J. M. TOWNE, AND F. W. WILSON.

BOOK COVER.

Application filed October 11, 1924. Serial No. 742,984.

To all whom it may concern:

Be it known that I, JOHN SCHADE, a citizen of the United States, residing at Holyoke, county of Hampden, and State of Massachusetts, have invented certain new and useful Improvements in Book Covers; and I do declare the following to be a full, clear, and exact description of the invention, such as will enable others skilled in the art 10 to which it appertains to make and use the same.

My invention relates to book covers of the style and general construction exemplified in my pending application, Serial No. 15 654,300.

In said application the metal back and the side covers were equipped at their edges with complementary hinge eyes which were interengaged and then secured in hinging relation by means of a pintle inserted through the eyes, but in the present improvement, the metal back and the covers are provided with elements that are directly interlocked so as to effect a direct hinging with no pintle 20 whatsoever or anything else intervening.

The object of this invention is to provide a book cover, similar in appearance to that shown in said application, but in which the hinging is effected by interlocking elements 30 and not by elements that are interengaged and then secured by a pintle. In other words, my present structure does away with a pintle device since there are only two elements, one carried by the metal back and the 35 other carried by the covers, that effect the hinging.

In the accompanying drawings—

Figure 1 is an inside view of one form of my book cover with the covers in open position.

Figure 2 is a similar view of another form of my invention.

Figure 3 is a section at the line 3—3 of Figure 1.

Figure 4 is a section at the line 4—4 of Figure 2.

Figures 5 and 6 are fragmentary outside elevations of the structures shown at Figures 1 and 2 respectively.

Figures 7 and 8 are detail plans of the metal strips that are secured to the covers in the constructions shown at Figures 1 and 2 respectively, and

Figure 9 is a detail view of a metal back showing a modified form of opening therein. 55

Similar numerals of reference denote like parts in the several figures of the drawing.

Referring to Figures 1, 3 and 5, 1 is the metal back having at its side edges spaced openings 2. 3 are the covers having secured 60 to their inner edges in any suitable manner metal strips 4 from which project spaced fingers 5.

In assembling the book cover, these fingers are inserted through the openings 2 and 65 curled around, thus neatly hinging the covers to the back. In other words, one hinge element, the fingers, is interlocked with the other set of hinge elements, the openings, and then curled around. 70

In the construction shown at Figures 2, 4, and 6, spaced openings 6 are formed in projection 7 integral with the metal strips 4 that are secured to the covers, and spaced fingers 8 extend from the side edges of the 75 metal back, and in assembling, these fingers are inserted through said openings and curled around just as in the structure shown at Figure 1, so that it will be obvious that there is no material difference between the 80 book covers shown at Figures 1 and 2.

In order to give a more pleasing effect and a neater finish to the book cover shown at Figure 2, the projection 7 is slightly bent as shown. In the constructions shown at Figures 1 and 2 the openings consist of holes formed in the back plate or the projection, but the style of opening is immaterial, and at Figure 9 I have shown openings 9 that lend themselves to my invention equally as 90 well as the openings shown in Figures 1 and 2, and I therefore do not wish to be limited in this respect.

While it is preferred to make the back portion of metal, it is, of course, within the province of this invention to make this back of hard pressed cardboard, or stiff leather, with the holes cut therein to receive the interlocking hinge fingers that extend from the side covers, and these holes may be reinforced, if desired, by eyelets clinched therethrough. Or, a back made of material other than metal, might have a metal strip secured thereto in just the manner in which the similar strip is secured to the side cover portions, and this strip so secured to the 95 100 105

edges of the metal back might be provided either with holes or with the projecting fingers, according as the construction is of the style shown at Figures 1 or 2 respectively.

5 And since these possible changes are mere mechanical variations of my preferred structure and do not rise to the dignity of modifications, it is not deemed necessary to illustrate them.

10 What is claimed is:—

A book cover, comprising a metal back and penetrable side covers, said back having formed in its marginal side edges a series of

spaced openings, elongated metal strips from whose opposite side edges project spaced fingers and clinching members in staggered relation, said members being driven through the inner marginal edges of said covers and then clinched thereto, while said fingers are inserted through said openings in the back 15 and curled around to form hinge connections. 20

In testimony whereof I affix my signature hereto.

JOHN SCHADE.
